CLAIM

The ornamental design for vehicle seat, as shown and described.

DESCRIPTION

1.-2. Vehicle seat
1.1 : Bottom
1.2 : Front
1.3 : Perspective
1.4 : Left
1.5 : Right
1.6 : Top
1.7 : Back
2.1 : Left
2.2 : Right
2.3 : Back
2.4 : Bottom
2.5 : Top
2.6 : Front
2.7 : Perspective

1 Claim, 14 Drawing Sheets(56)
